UNITED STATES PATENT OFFICE.

MOFFAT CROOKS, OF ENFIELD WASH, PONDERS END, ENGLAND.

MEANS FOR LAUNCHING BOATS FROM SHIPS.

1,275,399.

Specification of Letters Patent. Patented Aug. 13, 1918.

Application filed March 16, 1915. Serial No. 14,709.

To all whom it may concern:

Be it known that I, MOFFAT CROOKS, armorer staff sergeant, a subject of the King of Great Britain, and a resident of 52 Putney road, Enfield Wash, Ponders End, Middlesex, England, have invented new and useful Improvements in or Relating to Means for Launching Boats from Ships, of which the following is the specification.

10 This invention relates to improvements in or relating to launching mechanism for ships' lifeboats and particularly to means whereby the said boats may be automatically lowered and released.

15 The object of my invention is to provide means for more safely and effectively launching ships' boats, whereby the loss of life frequently occurring by overcrowding of the lifeboats so causing them to be 20 swamped on entering the water, may be prevented, and consists in automatically lowering the said boats when each contains the number of passengers it is designed to carry. A further object of this invention 25 comprises the employment of a plurality of floats arranged around the boat and adapted to release the said boat at the moment it becomes buoyant.

In carrying my invention into effect I 30 support the lifeboat in a cage or cradle the said cage or cradle being provided with preferably four hooks or the like, adapted to pass through eyes or the like attachments secured in any suitable way to the lifeboat.

35 The said hooks after passing through the eyes are locked in position by hooks, keys, or the like, placed through suitably formed slots in the said supporting hooks. These said locking hooks are provided with a long

40 shank or extension adapted to depend outwardly on the outside of the said boat. On the end of the said shank or extension I provide a float of wood, cork, or other suitable buoyant material, adapted to hang 45 slightly lower than the keel of the boat.

Attached to the said cage is a supporting or lowering cable which cable passes over a davit or arm and thence to a drum upon which it is wound.

50 The said drum is rotatably mounted upon a shaft between suitable bearings and has formed therewith a brake drum of suitable construction. Embracing the said brake drum is a spring loaded band brake, so ar-

55 ranged as to prevent the lowering drum from rotating until a predetermined load is placed

in the boat. This predetermined load is the weight of the boat when containing the number of passengers that it is designed to carry with safety. When therefore the boat contains this number the load will overcome the friction of the brake upon the lowering drum and the boat will be slowly lowered until it reaches the surface of the water.

On the boat reaching the water the floats attached to the locking hooks of the supporting cage will tend to float and move the said locking hook or hooks upwardly out of engagement. This disengagement will not take place until the weight suspended upon the hooks of the cage is released due to the boat becoming buoyant. As soon as this takes place the release floats will come up to the surface of the water, thereby releasing the hooks of the cage and leaving the lifeboat free.

In order to prevent the lifeboat being released or shifted due to rough weather, and to prevent undue stress upon the band brake I provide means for locking the lowering drum when not in use. This locking device may be of any suitable construction, and it is preferably connected to a plate or board on the deck-side of the vessel in such a manner that the action of a person stepping upon the said plate, throws the said locking device out of engagement with the said lowering drum leaving the drum free to rotate when the predetermined load to be carried by the boat, is reached.

The davit or arm over which the supporting cable passes is preferably placed at an angle to the vertical plane in order that it may swing outwardly when the boat is being lowered.

I provide a channel or the like at the side of the vessel having a rod or connecting piece or the like forming a guide for the supporting cage, in order to prevent the boat being smashed by striking against the side of the vessel, and also to prevent it being launched broadside on.

Stowing arms having two hooks depending outwardly from the side of the ship are provided in order to hold the boat in position against the ship's side when not in use.

And in order that my invention may be clearly understood, reference should be made to the appended sheets of drawings in which—

Figure 1 is an elevation of a portion of

- the side of a vessel showing the lifeboat in its normal position.
- Fig. 2 is an end view of the boat shown in Fig. 1.
- 5 Fig. 3 is a plan view of the lifeboat shown in Fig. 1.
- Fig. 4 shows one form of davit which may be employed in connection with this invention.
- 10 Fig. 5 is a section of the boat-carrying cradle or cage shown on a larger scale to illustrate more clearly the releasing mechanism.
- 15 Fig. 6 is an elevation of the lowering drum.
- Fig. 7 shows the position of the board or plate mounted upon the deckrail of the vessel for releasing the locking mechanism of the lowering drum.
- 20 Fig. 8 shows the end portion of the lowering drum to a larger scale to illustrate the locking device.
- Fig. 9 is an end view of the lowering drum shown in Fig. 8.
- 25 Fig. 10 illustrates a second method of supporting the lifeboat from two davits instead of one as previously illustrated.
- Referring to Figs. 1, 2 and 3, A is the lifeboat of usual and known construction supported by a cage or cradle B. The said cage or cradle is provided with four supporting arms or lugs having eyes, slots or the like B¹, through which hooks C¹ are adapted to pass. The said hooks are connected by means of chains D¹ to a common ring D which is secured in the usual manner to the supporting rope E.
- 30 Each of the supporting hooks C¹ after passing through the eyes B¹ (Fig. 5) are locked in position by hooks or keys H¹ placed through the holes or slots cut in the said supporting hooks C¹. The said locking hooks H¹ are provided with a long downwardly depending shank or extension
- 35 which is adapted to hang on the outside of the boat.
- 40 I provide at the end of the said shank or extension H², a float H³ of suitable buoyant material adapted to hang slightly lower than the keel of the boat.
- 45 The supporting rope or cable E passes from the davit F to the lowering drum G, upon which it is wound.
- The said drum G (shown on a larger scale in Fig. 6) is mounted between suitable bearings G¹ G² and is provided at one end with a brake drum L embracing which is a band brake L¹. The said band brake is provided at one end with a spring L² of such load and so arranged as to prevent the drum G from rotating until a predetermined load is put upon the supporting cable E. This load is the weight of the boat when containing the number of passengers that it is designed to carry with safety. When therefore the
- boat contains this number the load will overcome the friction of the band brake L¹ on the lowering drum G, and the boat will be slowly lowered until it reaches the surface of the water. On the boat reaching the water the floats H³ attached to the locking hooks H¹ of the supporting cage B will tend to float and move the said locking hooks upwardly out of engagement. As soon as this takes place the supporting hooks C¹ of the cage will be released and the lifeboat will be left free.
- In order to prevent undue stress upon the band brake L¹, I provide means for locking the lowering drum G when not in use. This locking device shown in Figs. 8 and 9 consists of a pivotally mounted arm or lever S having a pin S¹ at its end adapted to engage suitably formed holes or slots S² in the end plate of the lowering drum G. The spring S³ keeps the pin S¹ normally in engagement with one of the holes S².
- The lever S is connected by means of a wire or cable R to a plate or board T mounted upon the deckrail of the vessel (see Fig. 7) in such manner that the action of a person stepping upon the said plate will move the lever S and the pin S¹ out of engagement with the holes or slots S², thus leaving the drum G free to rotate when the predetermined load is exerted upon the cable.
- In order to prevent the lever S¹ resuming its normal position when the board T is released, I provide a short bolt or the like V (Fig. 9) mounted in a bearing V¹ and provided with a spring V² adapted to abut against a shoulder V³ causing the end of the bolt V to abut against the lever S. The position of the bolt V is such that on the lever S being pulled back the spring bolt V will be released and will intercept the said lever in such manner that it will be prevented from regaining its normal position.
- I provide a channel W, preferably of T-section at the side of the vessel down which a block W¹ is adapted to slide. The said block is connected by means of a rod or the like Q to the supporting cage A in such manner as to prevent the boat being smashed by striking the side of the vessel or being launched broadside on.
- 55 Stowing arms P are provided and depend outwardly and downwardly from the side of the vessel and are connected by means of short links O to the said supporting cage, in order to hold the boat in position against the ship's side when not in use.
- 60 Referring to Fig. 4 a davit or arm F from which the supporting cable passes is preferably placed at an angle to the vertical plane, in order that it may swing outwardly when the boat is being lowered. A stop or lug F¹ which abuts against the side of the vessel when the said davit is in its "out-

ward" or lowering position is provided to prevent said davit swinging farther than the desired distance.

Fig. 10 shows a modification of this arrangement in which two davits are employed for the purpose of supporting and lowering the said boat.

In this arrangement the supporting cable may be conveniently wound upon separate drums mounted upon a common spindle and controlled by one brake in such manner that each end of the boat will be lowered simultaneously and will therefore remain in horizontal position when being lowered.

As illustrated in Fig. 5 the name of the vessel to which the boats are attached may be painted or stamped upon each releasing float in order that should the vessel founder at sea, these said floats may be a means of identification.

What I do claim as my invention and desire to secure by Letters Patent is:—

1. Launching mechanism for ship's boats including a drum and a boat supporting cable connected with the drum, in combination with means constructed and arranged to hold the drum against rotation and acting automatically to permit rotation of the drum when a predetermined weight is applied to the cable.

2. Launching mechanism for ship's boats including a drum and a boat supporting cable connected therewith, in combination with an automatic friction brake operatively associated with the drum, said friction brake being adjusted to hold the drum against rotation, and acting automatically to permit a gradual unwinding of the cable from the drum when a predetermined weight is applied to the cable.

3. Launching mechanism for ship's boats including a drum and a boat supporting cable connected therewith, means for positively locking the drum against movement including a pivoted locking member, a spring

acting to maintain the locking member in locking engagement with the drum, manually operable means for moving the locking member out of engagement with the drum, a sliding latch for said locking member said latch being adapted to rest against the locking member when the locking member is in locking engagement with the drum, a spring acting to maintain the latch in position against the locking member and move the latch in the path of the locking member to hold the locking member in an inoperative position.

4. The combination with a ship of boat launching apparatus including a drum, a boat supporting cable connected therewith, locking means for holding the drum against movement, a member pivotally supported and operatively connected with said locking means, said member being adapted to be actuated to release the locking means by a person stepping thereupon, and means acting automatically to engage and hold said locking means out of locking engagement with the drum.

5. Launching apparatus for ship's boats including boat supporting and lowering mechanism acting automatically to lower the boat when it contains a specified number of passengers.

6. An apparatus for launching boats, in combination with a ship having a vertically extending guide way on the exterior thereof, of a drum, a boat supporting cable connected therewith, a boat supporting cradle arranged to embrace the sides of a boat and connected with said supporting cable, a member slidably engaging the said vertical guide and a link pivotally connected with the said boat supporting frame and with the said member, substantially as described.

MOFFAT CROOKS.
